[57] ABSTRACT

A manually operable tube bender having a male clamp portion adapted to be clamped fixedly in a female clamping device for supporting the tube bender during a tube bending operation. The clamp element is interconnected with the mandrel of the tube bender by a connector portion. In one form, a hook is formed integrally with the male clamp portion and in a second form, the hook is pivotally associated therewith.

FIG. 10

FIG. 12

TUBE BENDER

BACKGROUND OF THE INVENTION

1. Field of the Invention

This invention relates to tube benders and in particular to manually operable tube benders.

2. Description of the Prior Art

In the conventional manually operable tube benders of the prior art, a shoe is swingably associated with a mandrel having a peripheral groove so as to press the tube to be bent into the groove as the shoe is swung thereabout. A handle is attached to the shoe and a second handle is attached to the mandrel. The tube is held against longitudinal movement during the bending operation by a hook which is disposed against a starting position of the bend and against which the tube is urged by the forces generated by the sliding movement of the shoe against the tube surface. Excellent examples of such tube benders are shown in the U.S. Patent owned by the assignee hereof, including Robert D. McIntosh U.S. Pat. No. 2,428,237; Joseph H. Zales et al. U.S. Pat. No. 2,757,562; Leonard J. Kowal et al. U.S. Pat. No. 2,796,784; Howard L. Philippe U.S. Pat. No. 2,796,785 and U.S. Pat. No. Re. 24,449; Leonard J. Kowal U.S. Pat. No. 2,887,917; Julius Gryniewicz U.S. Pat. No. 2,908,193; George E. Franck U.S. Pat. No. 2,979,976; Alfred R. Landis U.S. Pat. No. 2,986,195; George E. Franck U.S. Pat. No. 3,051,218; George E. Franck et al. U.S. Pat. No. 3,077,221; Leonard J. Kowal U.S. Pat. No. 3,685,335; and Leonard J. Kowal et al. U.S. Pat. No. 3,750,447.

Illustratively, in the Franck et al. U.S. Pat. No. 3,077,221, the hook is swingably mounted to the mandrel, and in Kowal U.S. Pat. No. 3,685,335 and Kowal et al. U.S. Pat. No. 3,750,447, the hook is fixedly associated with the mandrel.

In Franck U.S. Pat. No. 2,702,065, a tube bending apparatus is shown having a base which may be clamped in a vise. A somewhat similar base adapted to be clamped in a vise is shown in Franck U.S. Pat. No. 2,762,415 (Re.27,426).

SUMMARY OF THE INVENTION

The present invention comprehends an improved manually operable tube bender including a one-piece combination mandrel support and tube holder providing a facilitated tube bending operation and permitting facilitated use of the tube bender with the combination structure fixedly secured in a female clamping device. The tube bender is arranged for facilitated swinging of the shoe in the tube bending operation with the structure so held.

Adjustable stop means may be provided for positioning the end of the tube to be bent in a preselected relationship to the mandrel groove. In one form, the adjustable stop means is carried on the means securing the mandrel support and tube holder to the mandrel, and in another form, the stop means is carried on a post mounted to the mandrel support and tube holder structure.

In one form, the hook portion is formed integrally with the clamp element adapted to be clamped in the female clamping device. In another form, the hook element is swingably mounted thereto.

In one form, a mounting wall is provided adjacent the mandrel and the hook portion is swingably mounted thereto.

The securing means may comprise an elongated post having a threaded end secured to the mandrel and adapted to carry the adjustable stop. Alternatively, the mandrel support and tube holder may be secured to the mandrel by a threaded means and the post may be secured to the mandrel support independently thereof.

In one illustrated embodiment, the mandrel support and tube holder structure comprises an L-shaped block with the tube holder formed integrally therewith as a recess in one end edge portion of the block.

The tube bender of the present invention is extremely simple and economical of construction while yet providing an improved facilitated tube bending operation.

BRIEF DESCRIPTION OF THE DRAWING

Other features and advantages of the invention will be apparent from the following description taken in connection with the accompanying drawing wherein:

FIG. 1 is a side elevation of a tube bender embodying the invention;

FIG. 2 is a bottom plan view thereof;

FIG. 3 is a fragmentary side elevation of a modified form of tube bender embodying the invention;

FIG. 4 is a bottom plan view thereof;

FIG. 5 is a fragmentary side elevation of still another modified form of tube bender embodying the invention;

FIG. 6 is a bottom plan view thereof;

FIG. 7 is a fragmentary side elevation of yet another modified form of tube bender embodying the invention;

FIG. 8 is a bottom plan view thereof;

FIG. 9 is a fragmentary side elevation of a still further modified form of tube bender embodying the invention;

FIG. 10 is a bottom plan view thereof;

FIG. 11 is a fragmentary side elevation of yet a further modified form of tube bender embodying the invention; and

FIG. 12 is a bottom plan view thereof.

DESCRIPTION OF THE PREFERRED EMBODIMENTS

In the exemplary embodiment of FIGS. 1 and 2, a manually operable tube bender generally designated 10 is shown to comprise a mandrel 11 having an arcuate tube bending groove 12. A shoe 13 is swingably connected to the mandrel by a link 14 and is manipulated by means of an elongated handle 15. Link 14 is pivotally connected to shoe 13 by a pivot 16 and to the mandrel by a pivot 17. The tube T to be bent is urged into the mandrel groove 12 by movement of the shoe 13 thereagainst as the shoe is swung from a bend-start position 18.

Tube T is held against a longitudinal movement during the tube bending operation by a hook 19. As shown in FIGS. 1 and 2, hook 19 comprises an integral portion of a one-piece combination mandrel support and tube holder structure generally designated 20.

Structure 20 comprises an L-shaped block having a first portion 21 defining a male clamp element adapted to be clamped fixedly in a female clamping device, such as a vise. Block 20 further includes a second portion 22 having an end edge portion 23 defining a recess 24 forming hook 19 integrally with structure 20. End edge portion 23 further defines a connector 25 which is fixedly secured to mandrel 11 by means of suitable threaded means, such as screw 26, so as to dispose

hook 19 in alignment with the bend-start point 18, as best seen in FIG. 1.

The threaded securing means 26 is thusly disposed remotely from the male clamp portion 21, as best seen in FIG. 2, for facilitated tube bending operation of the tool.

Thus, as shown in FIG. 1, with the clamp portion 21 disposed lowermost, such as between the female clamping elements of a supporting vise or the like, the hook 19 is disposed substantially forwardly thereof for facilitated bending of the tube T.

Referring now to the embodiment of FIGS. 3 and 4, a tube bender generally designated 110 is shown to comprise a tube bender generally similar to tube bender 10 but having a modified securing means 126 for fixedly securing the connector portion 125 to the mandrel 111. As shown in FIGS. 3 and 4, the securing means may comprise a post 127 having a threaded end 128 secured to the mandrel. The post includes an inner shoulder portion 129 clamping connector portion 125 to the mandrel when the threaded portion 128 is fully threaded thereto.

The post is elongate and carries an adjustable stop 130 defining a shoulder 131 against which the end of tube T may abut. The stop is slidably carried on post 126 and is fixed in the desired position by means of a suitable set screw 132. The position of stop 130 on the post is preselected for the desired tube bend and facilitates production of a series of such tube bends by accurately positioning each tube by the simple expedient of abutting the end thereof with the stop when the tube is inserted into the hook 119 and tube bending groove 112 of the mandrel 111.

A further modified form of the invention is shown in FIGS. 5 and 6 to comprise a manual tube bender generally designated 210 having a combination mandrel support and tube holder structure 220. Structure 220 differs from structure 20 of tube bender 10 in having a mounting wall 233 which defines connector 225 and a hook mounting portion 234. Connector 225 is secured to the mandrel 211 by screw 226 to dispose wall 233 in spaced relationship to the mandrel. A screw 235 is extended through the hook mounting portion 234 and threaded to the mandrel 211. Screw 235 includes a cylindrical shank portion 236 pivotally carrying a hook member 237 for engagement with the tube adjacent the bend-start position 218 of the mandrel, as shown in FIGS. 5 and 6. The hook is swung into engagement with the tube for facilitated disposition of the tube to be bent in the tool during the bending operation.

Referring now to the embodiment of FIGS. 7 and 8, a tube bender generally designated 310 is generally similar to tube bender 210 but having an adjustable stop 330 mounted on a post 327 and is shown to include a pivotal hook 337 carried on a screw 335 similarly to hook 237 and screw 235 of tube bender 210. Post 327 is threaded to the mandrel in a manner similar to the threading of post 127 to mandrel 111 of bender 110. Thus, tube bender 310 is similar to tube bender 110 in having an adjustable stop mounted on a post defining the means for securing the mounting structure to the mandrel, and similar to tube bender 210 in having a pivotal hook.

Referring now to FIGS. 9 and 10, another modified form of tube bender embodying the invention generally designated 410 is shown to comprise a tube bender generally similar to tube bender 310 but having a separate screw 426 for securing the mounting wall 433 to

the mandrel 411. The adjustable stop post 427 is secured to the block 420.

In the embodiment of FIGS. 11 and 12, a further modified form of tube bender generally designated 510 is shown to include a fixed hook 519 and an adjustable stop 530 carried on a post 527 secured to the mounting structure block 520. The connector portion 525 of the block is secured to the mandrel 511 by a suitable screw 526.

Each of the embodiments of FIGS. 3-12 is thusly similar to the tube bender 10 embodiment of FIGS. 1 and 2 and the elements thereof are identified by similar reference numerals but 100 different in the different embodiments. The tube benders function in the same manner except as discussed above, and each embodiment provides improved facilitated tube bending operation while yet defining an extremely simple and low cost tube bender structure.

The foregoing disclosure of specific embodiments is illustrative of the broad inventive concepts comprehended by the invention.

I claim:

1. In a manually operable tube bender having a mandrel provided with a peripheral tube receiving groove, a shoe swingably mounted to said mandrel, and a handle for swinging said shoe about said mandrel for urging a tube into said groove in a tube bending operation, the improvement comprising:

a one-piece combination mandrel support and tube holder having a first integral portion defining a male clamp element adapted to be clamped fixedly in a female clamping device for supporting the tube bender during a tube bending operation, a second integral portion defining a hook adapted to be engaged by the tube for preventing longitudinal movement thereof during the tube bending operation, and a third integral portion defining a connector; and

securing means for fixedly securing said connector to said mandrel.

2. The tube bender of claim 1 wherein said combination mandrel support and tube holder comprises a block having an edge portion provided with a recess defining said hook.

3. The tube bender of claim 1 wherein said combination mandrel support and tube holder comprises an L-shaped block having an end edge portion provided with a recess defining said hook.

4. The tube bender of claim 1 wherein said securing means is spaced substantially from said first portion of the combination mandrel support and tube holder.

5. The tube bender of claim 1 further including adjustable stop means carried by said combination mandrel support and tube holder in alignment with said hook for positioning the end of the tube to be bent in a preselected relationship to said mandrel groove.

6. The tube bender of claim 1 further including adjustable stop means carried by said securing means in alignment with said hook for positioning the end of the tube to be bent in a preselected relationship to said mandrel groove.

7. The tube bender of claim 1 further including adjustable stop means carried by said securing means in alignment with said hook for positioning the end of the tube to be bent in a preselected relationship to said mandrel groove, said securing means comprising an elongate post having a threaded end secured to said mandrel.

8. The tube bender of claim 1 further including adjustable stop means carried by said securing means in alignment with said hook for positioning the end of the tube to be bent in a preselected relationship to said mandrel groove, said securing means comprising an elongate post and said adjustable stop includes shoulder means slidably mounted thereon.

9. The tube bender of claim 1 further including a adjustable stop means including a post secured to said combination mandrel support and tube holder and adjustable shoulder means on said post in alignment with said hook for positioning the end of the tube to be bent in a preselected relationship to said mandrel groove.

10. In a manually operable tube bender having a mandrel provided with a peripheral tube receiving groove, a shoe swingably mounted to said mandrel, and a handle for swinging said shoe about said mandrel for urging a tube into said groove in a tube bending operation, the improvement comprising:

a one-piece support having a first integral portion defining a male clamp element adapted to be clamped fixedly in a female clamping device for supporting the tube bender during a tube bending operation, and a second integral portion defining a connector;

first securing means for fixedly securing said connector to said mandrel;

a hook adapted to be engaged by the tube for preventing longitudinal movement thereof during the tube bending operation; and

second securing means for movably securing the hook to said support adjacent said connector.

11. The tube bender of claim 10 wherein said support defines a mounting wall spaced adjacent said mandrel defining said connector and a hook mounting portion adjacent said connector, said hook being mounted to said hook mounting portion.

12. The tube bender of claim 10 wherein said support defines a mounting wall spaced adjacent said mandrel,

said second securing means comprises a pivot element extending between said mounting wall and said mandrel, and said hook is pivotally mounted on said pivot element.

13. The tube bender of claim 10 wherein said support defines a mounting wall spaced adjacent said mandrel, said connector portion comprising an extension of said mounting wall.

14. The tube bender of claim 10 further including adjustable stop means carried by said support in alignment with said hook for positioning the end of the tube to be bent in a preselected relationship to said mandrel groove.

15. The tube bender of claim 10 further including adjustable stop means carried by said first securing means in alignment with said hook for positioning the end of the tube to be bent in a preselected relationship to said mandrel groove.

16. The tube bender of claim 10 further including adjustable stop means carried by said first securing means in alignment with said hook for positioning the end of the tube to be bent in a preselected relationship to said mandrel groove, said first securing means comprising an elongate post having a threaded end secured to said mandrel.

17. The tube bender of claim 10 further including adjustable stop means carried by said first securing means in alignment with said hook for positioning the end of the tube to be bent in a preselected relationship to said mandrel groove, said first securing means comprising an elongate post and said adjustable stop means includes shoulder means slidably mounted thereon.

18. The tube bender of claim 10 further including adjustable stop means including a post secured to said support and adjustable shoulder means on said post in alignment with said hook for positioning the end of the tube to be bent in a preselected relationship to said mandrel groove.
